NUT-HOLDING WRENCH

Raymond M. Martorella, Millbrae, Calif.

Application February 16, 1954, Serial No. 410,687

2 Claims. (Cl. 81—112)

This invention relates to a nut wrench and more particularly to a wrench having a nut grip therein.

An object of this invention is to provide an improved wrench having outwardly biased springy arms mounted in axially extending grooves in the surface of a handle and moved inwardly by an axially slideable sleeve to grip and hold the nut during removal and application, said wrench also being capable of receiving and retaining a wing nut for application to or removal of a bolt.

A further object of this invention is to provide a nut wrench which is simple and efficient in construction, and durable and lasting in use.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the improved nut wrench forming the subject of this invention;

Figure 2 is a sectional view taken substantially along the section line 2—2 of Figure 1;

Figure 3 is an end elevational view from the socket end of the wrench with the retaining sleeve in retracted position;

Figure 4 is an end elevational view from the socket end showing the retaining arms engaging a square nut disposed within the socket; and

Figure 5 is a view similar to Figure 4 but showing a hexagonal nut disposed within the socket.

Referring now more particularly to the accompanying drawings, it will be seen that the improved nut wrench forming the subject of this invention includes, a handle 10 having a socket assembly 12 secured to one end thereof. The handle 10 is provided with a recess 14 extending longitudinally thereof and opening from one end of the handle.

The socket assembly 12 comprises an elongated pin 16 which is adapted to be forced within the recess 14 and to be rigidly maintained therein. The pin 16 is rectangular in cross section so as to be non-rotatably mounted within the handle 10. A portion 18 of the pin 16 extends beyond the end of the handle 10. A socket 20 having an aperture 22 is adapted to be received on the portion 18 of pin 16. A bushing 24 is disposed on the portion 18 of the pin 16 for frictionally engaging the inner periphery of aperture 22 to retain the socket 20 in position on the pin 16. The socket 20 is provided at its outer end with a circular recess 26 opening on the outer end of the socket. The extreme outer end of the recess 26 may be flared outwardly as at 28 so as to more easily allow the insertion of a nut within the recess 26. Extending from the outer end of the socket 20 at diametrically opposite points on the sides thereof are a pair of slots 30. The slots 30 permit the insertion of a wing nut 32, indicated in dotted lines in Figure 2, within the recess 26.

The end of handle 10 adjacent the socket 20 is provided with a reduced portion 34 which receives thereon a ring 36 having an outer diameter equal to the diameter of the handle 10. This ring 34 prevents the spreading of the handle 10 due to the stresses imparted thereto when a nut is being tightened on a bolt.

Means are provided for retaining nuts within the recess 26. This means comprises cutout portions 38 dis-

2

posed at diametrically opposite points on the handle 10 and in alignment with the slots 30. The cutout portions 38 converge inwardly away from the end of the handle 10 having the socket 20 mounted thereon. Resilient arms 40, formed of spring steel, or the like, are secured at one end to the deepest portion of cutouts 38. The arms 40 extend toward the socket 20 and are provided with finger portions 42 extending inwardly toward each other and which are adapted to be moved into the slots 30 for gripping a nut placed in the recess 26. The handle 10 is provided with a transverse aperture 44 extending between the deepest portions of the cutouts 38 and the pin 16 is provided with an aperture 46 in alignment with the apertures 44. A bolt 48 having a head 50 is adapted to extend through the fixed ends of the arms 40 and through the apertures 44 and 46. A nut 52 is threadedly engaged on the end of bolt 38 opposite the head 50 to retain the arms 40 in position on the handle 10. Suitable washers 54 may be disposed between the head 50 and one arm 40 and between the nut 52 and the other arm 40.

Means are provided for urging the finger portions 42 into the slots 30. This means comprises a sleeve 56 slidably disposed on the handle 10. When the sleeve 56 is urged toward the socket 20, engagement of the end of the sleeve 56 with the arms 40 will cause the arms 40 to be moved against the ring 36 and consequently the portions 42 will be urged into the slots 30. In order to limit the movement of sleeve 56 in a direction away from the socket 20 a ring 58 is fixedly secured to the handle 10 at a point remote from the socket 20. Suitable pins 60 extend through the ring 58 and into the handle 10 for locking the ring 58 in position.

As seen in Figure 4, the nut wrench forming the subject of this invention can be used in conjunction with a square nut 62 and as seen in Figure 5 the wrench can be used in conjunction with a hexagonal nut 64.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A nut wrench comprising a handle, a socket secured to one end of said handle and opening in the direction away from said handle, said socket being provided with a pair of diametrically opposed slots in the sides thereof, said slots being open in the same direction as said socket, and means mounted on said handle for movement into and out of said slots for engaging a nut disposed in said socket, said means including a pair of resilient arms secured to said handle and extending therefrom in overlying relationship to said slots, the free ends of said arms being provided with portions extending toward each other for movement into and out of said slots, said handle being provided with a sleeve slidably mounted thereon for movement therealong to a position overlying said inner arms to force the free ends thereof into said slots, said handle being provided with a pair of diametrically opposed cutout portions adjacent the end having the socket secured thereto, said resilient arms having one end secured in said cutout portions, said cutout portions tapering outwardly toward said one end of said handle.

2. The combination of claim 1 wherein said handle is provided with a stop thereon for limiting the movement of said sleeve in a direction away from said socket.
